UNITED STATES PATENT OFFICE.

THOMAS P. BROOKE, OF CHICAGO, ILLINOIS, ASSIGNOR TO THE BROOKE AIRCRAFT COMPANY, A CORPORATION OF DELAWARE.

FLYING-BOAT.

1,263,846.

Specification of Letters Patent. Patented Apr. 23, 1918.

Application filed May 17, 1916. Serial No. 97,991.

To all whom it may concern:

Be it known that I, THOMAS P. BROOKE, a citizen of the United States, residing at Chicago, in the county of Cook and State 5 of Illinois, have invented certain new and useful Improvements in Flying-Boats, of which the following is a specification.

This invention relates in general to improvements in flying boats, but more particularly to improvements in the hydroplane or bottom of the boat, and also the means for mounting, housing and cooling the motor therein, and one of the objects of the invention is to provide improved means for 10 causing the machine to readily and quickly rise or plane upon the water, and improved means for overcoming or preventing excessive resistance or "drag" on the machine while traveling in the air.

20 A further object is to provide an improved device of this character having a streamlined limousine body or cabin and in which structure the motor is so located as to be always accessible during flight.

25 A further object is to place the motor down in the boat body to obtain a low center of gravity and at the same time completely house the motor by the boat body.

A still further object is to provide improved means whereby the motor will be 30 cooled by the action of the propeller blades. Also that there will be no resistance caused by projecting parts of the motor or radiators.

35 To the attainment of these ends and the accomplishment of other new and useful objects as will appear, the invention consists in the features of novelty in substantially the construction, combination and arrangement of the several parts hereinafter 40 more fully described and claimed and shown in the accompanying drawings, illustrating the invention and in which:

Figure 1 is a side elevation of an improved flying boat body or boat of this character constructed in accordance with the principles of this invention and with some of the parts in section.

Fig. 2 is a bottom plan view of the structure shown in Fig. 1.

Fig. 3 is a top plan view of the parts shown in Fig. 1 and with parts broken away.

Fig. 4 is a view taken on line 4-4, Fig. 1.

55 Fig. 5 is a view taken on line 5-5, Fig. 2.

Fig. 6 is a view taken on line 6-6, Fig. 2.

Fig. 7 is a detail front elevation as taken from the right end of Fig. 1.

Fig. 8 is a detail vertical sectional view taken on line 8-8, Fig. 1. 60

Fig. 9 is a detail vertical sectional view taken on line 9-9, Fig. 1.

Fig. 10 is a detail vertical sectional view taken on line 10, 10, Fig. 1.

Fig. 11 is a detail vertical sectional view 65 taken on line 11-11, Fig. 1.

Fig. 12 is a detail vertical sectional view taken on line 12-12, Fig. 1.

Fig. 13 is a vertical sectional view on the line 13-13, Fig. 14. 70

Fig. 14 is a detail horizontal sectional view on line 14-14, Fig. 13.

Referring more particularly to the drawings, the numeral 15 designates generally the boat body, projecting from and suitably attached thereto are planes or wings 16. 75

The propeller 17 of any desired or approved type, is arranged at the rear of the planes or wings 16, and this propeller is operated in any suitable manner, such as by 80 means of a vertical shaft 18, of a motor to be hereinafter referred to and which motor is situated within the body 15 of the machine, in order to obtain a low center of gravity and at the same time completely 85 house the motor by the boat body, thereby dispensing with the necessity of mounting the motor upon the superstructure, where it would be subject to the action of the air currents in such a way as to result in excessive resistance, besides being located in a 90 position where it would be inaccessible during flight.

The main portion 15 of the body terminates adjacent the rear edges of the wings or 95 planes and is constructed to form adjacent the forward part thereof, a cabin 22 within which are arranged suitable seats 23. The

forward part of the body is preferably curved upwardly as shown and the bottom 100 of the body is shaped to form steps 24, 25, as shown more clearly in Figs. 5 and 6. The

rear step 25 is flat and is located adjacent the end of the main portion of the body while the step 24 is V-shaped and located approximately at the central point of the 105 main portion of the body between the step 25 and the bow of the boat. The

portion of the bottom of the body between the steps 24, 25 and on each side of 110 the center is flat and inclined upwardly in a forward direction as at 27, while the re-

mainning portion of the body between the step 24 and the bow of the boat on each side is straight and diverges from the center toward the sides of the body, and the angle 5 of divergence, gradually increases in a direction lengthwise of the body from the flat portion at the extreme top of the prow toward the V shaped step 24, as at 28, 29 and 10 30 in Figs. 9, 8 and 10. The upright portion of the V shaped step 24 is provided with a series of apertures or openings 32, which extend entirely across the bottom of the body, and the openings gradually decrease in size 15 from the center outwardly or toward the side of the body. The larger openings being arranged adjacent the center of the bottom permits a greater quantity of air to be supplied at that point than at the sides, and at a point where greater lifting force is necessary, and also at a point where less air is received 20 from the air that is drawn under the V portion of the boat bottom. A chamber 33 is arranged in the body adjacent these series of openings, and is provided with inlets 25 35 preferably in the form of tubes extending upwardly along the inside of the body, one on each side of the body and these inlets open through the sides of the body as at 36.

3. Funnels or shields 37 are provided to cover the inlet openings 36 and open toward the bow of the machine so that when the machine is advancing, whether in the air or upon the water, air will enter these funnels 35 under pressure and from there through the pipes 35 into the chamber 38 to be discharged in a horizontal direction through the openings 32 to flow along the bottom of the boat. The openings 32 are arranged in such 40 a manner that straight and substantially parallel streams of air will be discharged along and over the entire width of the bottom to form a continuous sheet of air bubbles between the boat's bottom and the surface of 45 the water to permit the boat to readily leave the water and will also overcome the "drag" or suction at the steps while the machine is in flight. Similar openings 38 are arranged in the upright portion of the step 25 to extend 50 transversely of the body and these openings 38 lead from a chamber 39 which is supplied with air through the pipes 40 having entrance openings through the sides of the body and over which openings are arranged 55 funnels 41, similar to the funnels 37, and which funnels also face toward the bow of the boat. The currents of air entering the chamber 39 will be discharged through the openings 38 to act in a manner similar to 60 the currents of air discharged through the openings 32.

It will thus be manifest that the streams of air which are discharged from these openings 32, 38, will prevent the formation of eddy currents, commonly known as "drag".

in the rear of the steps during flight and also serves the function of forming sheets of air bubbles upon which the body rolls while riding upon the water.

Furthermore, the slight flat portion of the 70 bottom at the extreme top of the prow, from which the bottom is shaped to form a pronounced V-shape terminating in an abrupt V step approximately midway of the length of the main portion of the body and which 75 gradually increases in contour from the prow backwardly, eliminates backward impact of the waves, and converts such power into an upward lifting action, thereby causing the craft to readily and quickly rise and plane 80 upon the water.

The rear 42 of the body 15, in the rear of the step 25, is preferably rectangular in construction and tapers from the body portion to the stern, and the sides and bottom of the rear portion of the body converge from the body portion. 85

If desired, a rudder 19 may be arranged uprightly at the end of the portion 42 and counterbalanced to move about pivots 20, 90 and this rudder may be moved about its pivot in any desired or suitable manner. A horizontal elevator 21 may be also provided if desired, adjacent the stern of the machine. The cabin in the body is provided with a 95 closure in the form of a roof 43, and is also provided with windows 44, and the forward part of the closure preferably comprises two top and side sections 45, 46, having transparent openings 47 therethrough. The sections are preferably hinged on upright pivots, so as to divide the roof of this portion into two sections that swing to open the forward portion of the cabin. The roof 43 of the rear portion of the cabin may be constructed so as to be quickly raised or opened to permit easy ingress and egress. Thus it will be manifest that in order to open the front of the cabin, all that is necessary is to swing the front and side sections 45, 46 105 about their pivots. This structure also gives the body or cabin a limousine effect. 110

The cabin is provided with an upright partition 48 which extends entirely there-across to form two compartments 49, 50, the 115 compartment 49 being adapted for passengers, while arranged within the compartment 50 is a motor arranged uprightly, so that the shaft will revolve in a vertical po-120sition and which motor is disposed within the body of the boat to be completely housed thereby and is connected with the propeller 17 by means of suitable gearing. The motor comprises a plurality of cylinders 51 and a partition 52 coöperates with the par-125tition 48 to form a compartment 50 and an-other compartment 53 on the side of the par-tition opposite to the compartment 50. The compartment 50 is provided with openings 54, having open hoods 54^a, suitably arranged 130

to form inlets for air, while the compartment 53 is provided with openings 55 which form outlets for air. The cylinders 51 are each provided with a casing 56 spaced from the walls of the cylinders and between which casings 56 and the cylinders 51 are arranged cooling flanges 57 which extend longitudinally of the cylinders and the cylinders, casings and flanges are so arranged that the 10 passages formed between the flanges constitute the only means of exit for the air which enters the compartment 50 through the openings 54. This air enters the compartment 50 under pressure and the action 15 of the propeller 17 revolving in close proximity to the outlet openings 55 of the compartment 53, creates an area of low pressure or vacuum adjacent the openings 55, and the suction created by the propeller will 20 cause the air to be drawn from the compartment 50 over the cooling flanges 57 and the cylinder walls into the compartment 53 and out of the openings 55.

The partition 48 is preferably provided 25 with doors 58 to permit access to the compartment 50, and it will thus be manifest that with the arrangement of the motor in an upright or vertical position, ready access may be had to the motor cylinders, 30 electrical system and carbureters through the doors 58 at all times and when the machine is in flight.

What is claimed as new is:

1. A machine of the character described, 35 embodying a body having a cabin therein, a roof therefor, the forward portion of the cabin and roof being shaped into freely separable sections, the rear portion of the roof of the passenger cabin being also sectional and adapted to be freely opened.

2. A machine of the character described, 40 embodying a body having a cabin therein, the upper and forward portion of the cabin and roof being shaped to form separable sections mounted to swing about upright pivots.

3. A machine of the character described, 45 embodying a body comprising a housing, the bottom thereof being shaped to form steps spaced longitudinally of the body and also spaced from the forward end thereof, and provision for forcing air currents through the upright portions of the steps, the portion of the bottom between the steps 50 and also at the extreme top of the prow for a short distance being flat, and the portion of the bottom between the said flat portions forming a straight line from the keel laterally to the edges of the body and diverging laterally from a medial line, at 55 inclined angles and gradually merging into said flat portion, at the prow.

4. A machine of the character described 60 embodying a body comprising a housing, the bottom thereof being shaped to form

steps spaced longitudinally of the body and also spaced from the forward end thereof, the bottom at the extreme top of the prow being flat, and the portion of the bottom between the steps being also flat and provisions for forcing air currents through the 70 upright portions of the steps, the portion of the bottom between the said flat portions forming a straight line from the keel laterally to the edges of the body and diverging laterally from a medial line, at inclined angles and gradually merging into said flat portion at the prow, the forward end of the said bottom being also shaped to form an upwardly extending curve. 75

5. A machine of the character described embodying a body comprising a housing, the bottom thereof being shaped to form spaced flat portions extending laterally of the bottom, one of said portions being located at the front of the body and extending but a short distance, and the other flat portion being midway of the bottom, the portion of the bottom between said flat portions forming a straight line from the keel 80 laterally to the edges of the body and diverging laterally at inclined angles from a medial line, one extremity of said inclined portion gradually merging into the flat portion at the front of the body and the other 85 extremity of said inclined portion forming an abrupt V shape at the edge of the flat portion midway of the body, the portion of the body in rear of the flat portion which is located midway of the body forming a 90 flat step and inclining upwardly in rear of the step toward the stern. 95

6. A machine of the character described embodying a body comprising a housing, the bottom thereof being shaped to form 100 spaced flat portions extending longitudinally of the bottom, one of said portions being located at the front of the body and extending but a short distance and the other flat portion being located midway of the 105 body, the portion of the bottom between said flat portions forming a straight line from the keel laterally to the edges of the body and diverging laterally at inclined angles from a medial line, one extremity of said inclined 110 portion gradually merging into the adjacent flat portion at the front of the bottom, the other extremity of the inclined portion forming an abrupt V shape, the portion of the body in rear of the flat portion which is located 115 midway of the body, forming a flat step and inclining upwardly in rear of the step and toward the stern, the forward end of said bottom being also shaped into an upwardly extending angle. 120

7. A machine of the character described embodying a body comprising a housing, the bottom thereof being shaped to form spaced flat portions extending longitudinally of the bottom, one of said portions 125

being located at the extreme top of the 65
prow and extending for only a short distance, the other flat portion being midway of the body, the portion of the bottom between 5
said flat portions forming a straight line from the keel laterally to the edges of the body and diverging laterally at inclined angles from a medial line, one extremity of said inclined portion gradually merging 10
into the adjacent flat portion of the body at the prow the other extremity of the said inclined portion forming an abrupt V shape, the portion of the body in rear of the flat portion which is located midway of the 15
body, forming a flat step and inclining upwardly in rear of the step toward the stern, the said flat portion of the bottom adjacent 20
said V inclining upwardly and forwardly.

8. A machine of the character described, 20
embodying a body, a propeller, a motor for actuating the propeller, said motor housed within the said body, and provisions whereby the operation of the propeller will induce a circulation of outside air across the motor 25
cylinder for cooling the motor, the said provisions embodying a casing arranged around and spaced from the motor cylinder, said casing having open ends, and flanges arranged between the cylinder and casing and 30
extending lengthwise thereof.

9. A machine of the character described embodying a body, having a compartment therein, a motor entirely housed within the compartment and arranged on an upright 35
axis, a partition dividing the compartment into separate chambers, there being air passages extending along the cylinder and forming the only source of communication between the two chambers, one of said chambers having an inlet opening for outside air, the other chamber having an outlet opening for the air, and a propeller operating adjacent said outlet opening whereby the operation of the propeller will cause the air to 40
flow from one of the chambers through the said air passages into the other chambers and out of the said outlet opening.

10. A machine of the character described, embodying a body having a compartment 50
therein, a motor arranged in the compartment and entirely housed thereby, a propeller, and provisions whereby the operation of the propeller will cause outside air to circulate into the compartment, across the motor cylinder and out of the compartment, said motor being arranged on a vertical axis and embodying a plurality of superposed 55
cylinders.

11. A machine of the character described, 60
embodying a body having a compartment therein, a partition dividing the compartment into separate chambers, a motor entirely housed within the compartment and

embodying a cylinder, air passages extending lengthwise of the cylinder and forming 65
communicating passages between the said chambers, there being an inlet in one of the chambers for outside air, there being an air outlet leading from the other chamber, the air entering the first said chamber under 70
pressure, and a propeller, said outlet opening being disposed adjacent the path of movement of the propeller whereby the propeller will create a suction through the said outlet. 75

12. A machine of the character described, embodying a body having a compartment therein, a partition dividing the compartment into separate chambers, a motor entirely housed within the compartment and 80
embodying a cylinder, air passages extending lengthwise of the cylinder and forming communicating passages between the said chambers, there being an inlet in one of the chambers for outside air, there being an air 85
outlet leading from the other chamber, the air entering the first said chamber under pressure, and a propeller, said outlet opening being disposed adjacent the path of movement of the propeller whereby the propeller will create a suction through the said outlet, the said walls of said compartment converging toward the propeller. 90

13. A machine of the character described embodying a hydroplane having a straight 95
flat portion at the extreme top of the prow, then shaped to form a pronounced V gradually increasing in contour from the prow backwardly, to eliminate backward impact of the waves and convert the same into an 100
upward lifting action, said graduated V-shaped portion terminating in an abrupt step approximately midway of the length of the main portion of the body, the portion of the hydroplane in advance of the step diverging laterally in straight lines at inclined angles from a medial line, the hydroplane in 105
rear of the step from the top line of the step inclining downwardly toward the stern and being flat, the rear portion of the hydroplane 110
at the end of the said downwardly inclining portion being offset upwardly, to form another and flat step spaced from the first step and longitudinally of the body, said rear portion being substantially flat and inclining upwardly toward the stern from a line at the top of the rear step. 115

In testimony whereof I have signed my name to this specification, in the presence of two subscribing witnesses, on this 27th day 120
of April, A. D. 1916.

THOS. P. BROOKE.
